UNITED STATES PATENT OFFICE.

JOSEPH L. DODD, OF CAMDEN, NEW JERSEY, ASSIGNOR OF ONE-HALF TO
ULYSSE C. MCKEE, OF CAMDEN, NEW JERSEY.

SCALE AND GAGE FOR PRINTERS' USE.

SPECIFICATION forming part of Letters Patent No. 691,715, dated January 21, 1902.

Application filed June 4, 1901. Serial No. 63,091. (No model.)

To all whom it may concern:

Be it known that I, JOSEPH L. DODD, a citizen of the United States, and a resident of Camden, Camden county, New Jersey, have ⁵ invented certain Improvements in Scales and Gages for Printers' Use, of which the following is a specification.

My invention relates to certain improvements in scales and gages for printers' use, ¹⁰ applicable more particularly for use in connection with lead-cutters and the composing-sticks in which type is set.

My invention is fully illustrated in the accompanying drawings, in which—

¹⁵ Figure 1 is a perspective view illustrating my invention as applied to a lead-cutter. Fig. 2 is a plan view showing the application of my invention to a composing-stick. Fig. 3 is an enlarged view of a portion of my invention, ²⁰ illustrating a detail thereof; and Figs. 4 and 5 are views of certain modifications of parts of the mechanism forming the subject of my invention.

In printing offices of the present day the ²⁵ scale of measurement is that which is known as the "point" system, in which twelve points equal one em pica, and six ems pica equal one inch, and the scale and gage which I have devised is adapted particularly for effecting measurements in the cutting of lead and the gaging of the width of lines of the type to be set on this scale.

The gage which I have constructed is adapted to be adjusted in one place in accordance ³⁵ with the pica measurements and in another place in accordance with the point measurements, and by the combination of these two scales I am enabled to effect measurements in points and pica of any required size within ⁴⁰ the limit of work required.

In the drawings herewith, 1 represents a suitable frame forming the bed of a lead-cutter, which frame is supported by means of a bracket 2, having the lower forked portion 3, ⁴⁵ adapted to engage the front rail 4 of a composing-frame, being held thereto by the thumb-screw 4^a. Pivotaly mounted at 5 on the end of this bed-frame is a knife-handle 6, carrying the movable knife 7, which coacts ⁵⁰ with the fixed knife 8, carried by the bed-plate 1. The handle 6 is adapted to the guide

9, and a spring 10 is employed for keeping the knife normally in the raised position.

Carried by the side of the bed-frame 1 is a triangularly-toothed rack, the teeth of which ⁵⁵ are shown at 11, and adapted to engage these teeth is a pawl 12, pivoted at 13 to a slide-piece 14, carried by the raised edge 15 of the bed-frame 1 and movable along said frame. This slide controls the position of the knee-⁶⁰ piece 16, which serves as the gaging-stop against which the leads to be cut are held. The pawl 12 is held in engagement with the teeth 11 of the rack by means of the catch 17, pivoted at 18 to the slide and having a suitable finger-piece 19, whereby it may be readily operated. In order to insure a positive holding of said pawls by the catch 17, the engaging faces of the parts are beveled at 20, as clearly shown in Fig. 1, and when once ad-⁶⁵justed the frictional contact is sufficient to hold them in positive engagement. The slide is so made as to move along the bed-frame 1, having portions contacting therewith on either side of the rack, and connecting these portions is the yoke-piece 21, to which both the pawl 12 and catch 17 are pivoted. The teeth ⁷⁰ 11 of the rack are formed with two beveled faces, and the pawl is beveled to engage such faces. While I do not wish to limit myself ⁷⁵ to this form of tooth, I prefer it, for the reason that if the points of the teeth wear as well as the point of the pawl the beveled faces of the latter engaging the beveled faces of the teeth will insure the centering of the pawl and ⁸⁰ the correct adjustment of the slide 14.

The parts just described provide for the adjustment of the knee-piece 16 in pica measurements, such measurements being the coarse adjustment of the gage. To provide for the ⁸⁵ fine adjustment in points, I arrange the knee-piece 16 so that it is movable with respect to the slide 14, each part having coacting portions divided in points. This is more clearly shown in Fig. 3, in which the knee 16 has the ⁹⁰ notched portion 22 divided into points, adapted to engage the notched portion 23 of the frame 14, also divided into points. Between the knee-piece 16 and the slide 14 is a space ⁹⁵ 24 the width of a pica, and by raising the catch 25 the knee-piece 16 may be adjusted to any one of the points and then secured by

turning said catch 25 down into place, as shown in Fig. 1.

In Fig. 2 I have shown the mechanism just described as applied to printers' composing-sticks 1^a. All the rest of the parts are similar to the structure shown in Fig. 1 and are lettered accordingly.

Instead of using the pawl and catch, as illustrated in Figs. 1 and 2, for holding the 10 slide and knee-piece to the pica-rack I may employ, as shown in Fig. 4, a spring 26, carried by the yoke-piece 21 and adapted to engage a pawl 27, pivoted to said yoke-piece, such spring serving to hold said pawl in engagement with the rack. When it is desired 15 to move the knee-piece, the frame 14 will be slid along without touching the spring 26.

In Fig. 4 I have also illustrated another 20 form of rack, in which the teeth 11^a are provided with an abrupt face on one side of the same. By the use of such teeth as these all danger of accidental movement of the knee-piece by pressure on the lead to be cut will be obviated. In connection with this form 25 of teeth I have shown the spring-controlled pawl 27, as above described, and as such pawl may only ride over the teeth in one direction I provide the pawl with a hooked end 28, so that it may be readily lifted to permit 30 adjustment in the other direction. The point-scale may also be provided with teeth of this character, and in lieu of the catch 25, as shown in Fig. 1, I may employ the spring 29, as shown in Fig. 5, such spring engaging the 35 depending arm 30 of the frame 14 and the extension 16^a of the knee-piece 16.

When desired to adjust the knee-piece along the point-scale, it is only necessary to move such knee-piece against the spring 29, releasing 40 the coacting racks 22 and 23 and permitting the movement of the said knee-piece 16 to the desired position.

In order to prevent any rise of the knee-piece during any operation of my improved 45 scale and gage, whether as a lead-cutter or composing-stick, I provide the slide with a projecting portion 31, extending over the knee-piece and partially covering the same in all of its adjusted positions.

50 As clearly pointed out in the specification and clearly shown in the drawings, the structure forming the subject of my invention is applicable with equal advantage to both a lead-cutter and composing-stick, and unless otherwise 55 specifically restricted the claims are to be construed as covering a lead-cutter and printers' composing-stick.

Having thus described my invention, I claim and desire to secure by Letters Patent—

1. The combination of a frame or bed for printers' use, a rack carried thereby, an adjustable stop carried by said frame, securing devices carried with said stop and adapted to 65 engage the rack, and means for adjusting said stop independently of the rack.

2. The combination of the frame or bed for printers' use, a rack carried by the same, a movable slide-frame carried by said bed, engaging means carried by said frame whereby 70 it may be held to the bed, a stop carried by the frame and held therewith, and means for adjusting said stop with respect to the movable frame.

3. The combination of the frame or bed for 75 printers' use, a rack carried thereby, a movable frame carried by the bed, a pawl carried by said frame and adapted to engage the rack and hold said movable frame in a pre-determined position, an adjustable stop or 80 knee-piece carried by said movable frame, means for adjusting said stop with respect to the movable frame, and means for locking the movable frame and the movable stop in their adjusted positions, substantially as de- 85 scribed.

4. The combination in a lead-cutter, having the bed-frame carrying a fixed knife, and a pivoted knife adapted to coact therewith, of an adjustable stop for determining the length 90 of the lead to be cut, a movable slide-frame carrying said adjustable stop, a rack carried by the bed-frame and serving to control the position of the movable frame, and a finer 95 rack arranged between said movable frame and the adjustable stop whereby said stop may be adjusted with respect to the movable frame.

5. The combination in a lead-cutter, of the bed-frame carrying a fixed knife and a pivoted knife adapted to coact therewith, of an adjustable stop for determining the length of the lead to be cut, a movable frame carried by the bed-frame and serving also to move the adjustable stop, a rack carried by the bed-frame, a pawl carried by the movable frame and adapted to said rack whereby the position of the movable frame may be controlled, and a finer rack arranged between the movable frame and the adjustable stop whereby 100 said adjustable stop is permitted movement with respect to the movable frame, and means carried by the latter for locking said stop in its adjusted position, substantially as de- 105 scribed.

6. The combination of the frame or bed for 110 printers' use, a rack carried by the same, a slide-piece adapted to the frame and carrying a gaging member, a pawl pivoted to the slide-piece and adapted to engage the rack, and a 115 pivoted catch also carried by the slide-piece and adapted to lock the pawl in place.

7. The combination of the frame or bed for 120 printers' use, a rack carried by the same, a slide-piece adapted to the frame and having 125 a portion spanning the rack, a pawl pivoted to the slide-piece and engaging the rack, and a pivoted catch for holding said pawl in place, said members having beveled engaging faces whereby the pawl will be securely held in 130 place against the rack.

8. In a gaging device for printers' use, a

bed or frame carrying a rack divided into
"pica" measurements, a slide-frame carried
by the frame and having means to engage
said rack, and a knee-piece controlled by the
slide and carrying a "point" rack coacting
with said slide.

5 In testimony whereof I have signed my

name to this specification in the presence of
two subscribing witnesses.
